UNITED STATES PATENT OFFICE.

LESLIE WALTER WELSFORD, OF MELBOURNE, VICTORIA, AUSTRALIA, ASSIGNOR TO
JAMES CLASON GATES, OF MELBOURNE, VICTORIA, AUSTRALIA.

MACHINE FOR MAKING PAPER BAGS.

1,400,587.

Specification of Letters Patent. Patented Dec. 20, 1921.

Application filed July 8, 1920. Serial No. 394,651.

To all whom it may concern:

Be it known that LESLIE WALTER WELSFORD, a citizen of the Commonwealth of Australia, and resident of 266 Post Office Place, 5 Melbourne, in the State of Victoria, Commonwealth of Australia, has invented certain new and useful Improvements in and Relating to Machines for Making Paper Bags, of which the following is a specification.

This invention relates to improvements in machines for making paper block bottom bags of the type commonly employed in the parceling of foodstuffs and the like.

15 The invention has been devised in order to provide improvements in structural elements and mechanical movements whereby output is increased, greater reliability in operation is insured, and liability of tearing of the 20 paper at certain periods of the ordinary process of manufacture is obviated.

The invention more particularly has reference to machines for the manufacture of paper bags having at the sides longitudinal 25 seams and at the bottoms "diamond" folds furnished with thumb bits and wherein said seams and thumb bits are secured by the use of an adhesive.

In order that the invention may be more 30 readily understood it will now be described with reference to the accompanying drawings in which:—

Figure 1 is a side elevation, and

Fig. 2 is a plan of the improved machine.

35 Fig. 3 is a view illustrating the driving gear.

Fig. 4 is a view in perspective illustrating the spring fork or tongue adapted to hold the bag blank open to facilitate the operation 40 of the diamond folder.

Fig. 5 is a side elevation of the gumming roller.

Fig. 6 is a view of the position of the rollers and guiding members employed in 45 the formation of a bag.

Fig. 7 shows the first position of the diamond fold with the thumb bits formed thereon.

Fig. 8 shows the second position of the 50 diamond fold, and

Fig. 9 illustrates the finished diamond fold.

Figs. 10 and 11 are sectional and end ele-

vations respectively of the cutting and creasing rollers.

55 Figs. 12 and 13 are views illustrating the bearings of the paper roll undercarriage.

Fig. 14 is a view illustrating the ball bearing bracket for the upper rollers.

Fig. 15 is a view in plan partly in section 60 of one of the paper supporting rollers.

Fig. 16 and 17 are views in plan and elevation respectively of the guide rollers to enable the paper to be folded around the 65 templet.

Figs. 18 and 19 are views illustrating the bearings for the train of rollers on the machine.

Fig. 20 is a view in perspective of the preferred form of knife employed for parting 70 the bag blank from the paper roll.

Fig. 21 shows enlarged cross-sectional views of two creasing rollers employed in the machine.

According to this invention a strong 75 framework 1 is provided. Rotatably mounted in bearings 2 fitted below one end of the frame are spindles 3 supporting rollers 4 with fixed or adjustable flanges 5 and disposed around these rollers 4 is a belt 6 which 80 forms a support for the paper roll 7 and at the same time gives a braking effect.

The paper strip 8 from the paper roll 7 passes around the guiding roller 9 and then around a further roller 11 where it comes 85 into contact with a spring operated paste roller 12 working in a paste box 13. The paste roller 12 is held up against the paper by means of an arm 14 connected to the spindle of the roller and which is under the 90 pull of a spring 15.

The paper strip 8 is then drawn upon the templet 16 around which it is manually folded in the first instance to form an overlapping longitudinal seam 17.

95 In order that different sized bags may be constructed, it will be obvious that the templet 16 may be fitted with detachable edge strips or other means for widening the same.

On either side of the templet 16 are 100 grooved guiding pulleys 17^a attached by the brackets 18 to a cross plate 19 connecting the beams of the frame 1 and these brackets 18 and consequently, the grooved pulleys 17^a are adjustable by the thumb nuts 20.

105 These rollers 17^a are therefore adapted

to be swung out of the way when first threading the paper on the templet 16 and when they are in position against the paper and particularly if slightly canted 5 they tend to draw the paper into shape around the templet 16 while if there are any cuts on the paper, the said rollers 17^a moving in the direction of the paper allow of free movement and at the same time effectively 10 guide the paper along the templet 16 and the paper leaves the latter in the form of a folded strip or tube.

Forwardly of the end of the templet 16 are two superposed rollers 21, 22 and the 15 folded paper passing between them is caused to be drawn between creasing and cutting rollers 23, 24. The top roller 23 is formed with the male ridge 25 while the lower roller 24 is formed with the female groove 26, the 20 crease thus formed being shown by the dotted lines 27 Fig. 7.

These rollers are also formed with angular grooves 28, 29 the lower roller 24 being formed with the male ridge 28 and the top 25 roller 23 being formed with the female groove 29 so forming the diagonal creases 30 in the bag blank as illustrated in Fig. 7.

These rollers 23, 24 are also provided with parting knives 31, 32 illustrated more 30 particularly in Figs. 11 and 20 and which are arranged to cut off from the advancing folded strip 8 a length sufficient to form a bag, the cutting member 31 on the top roller 23 being adapted to engage the edge of the 35 cutting member 32 of the lower roller 24. These cutters 31, 32 are formed with serrated surfaces 32^a, the teeth 32^b being adapted to pass within the recesses 32^c at the meeting edges of the knives 31, 32 and 40 so cut the bag blank from the strip 8 and with a finished serrated edge.

It will be obvious that the cutting teeth of the knives 31, 32 may be formed in any suitable manner provided the teeth of the 45 one member come opposite the tooth spaces of the other member to allow of a gradual and easy cut.

Formed on the knife 31 on the top roller 23 are spaced grooves 33 which allow the 50 arms of the forked spring tongue or rod 35 to pass therethrough so that when the cutting knives are in operation said rod 35 is pressed upwardly into the grooves 33, such operation forming the thumb bits 34 55 at the proper time and position.

The forked rod or tongue 35 is affixed to the templet 16 and extends forwardly therefrom through central recesses or 60 grooves 36 in the drawing rollers 21, 22 and 65 through similar grooves in the parting rollers 23, 24 and through the grooves 33 in the knife 31.

The spring tongue or fork member is provided with upwardly curved teeth 37 disposed immediately forwardly of the con-

tact point of the parting rollers 23, 24 while a hook member 38 extends downwardly from a support 39 connected to the frame immediately behind the teeth 37, so that as the bag is drawn through, the top portion 70 of the paper is brought into engagement with the hook 38 which folds the paper back into the position shown in Fig. 7. The bag then moves forwardly below the guiding tongue 40 which completes the 75 fold as illustrated in Fig. 7 and which passes within the cut or slit portion 35^a, see Fig. 7 and guides the bag blank between the rollers 41, 42. The top roller 41 is centrally 80 grooved as at 43 and is provided with projections 44 at the grooved surface, which projections 44 contact with a roller 45 receiving paste from the paste box 46, and these members 44 paste the edges 47 of the bottom of the paper fold as illustrated in 85 Fig. 7. Simultaneously, the bottom of the bag is creased as at 48, Figs. 8 and 9, by the male ridges 49 on the top roller 41, and the female grooves 50 on the lower roller 42.

As the bag end passes through the rollers 90 41, 42, it is engaged by the member 51 of the hook 52 connected to the frame and the portion 53 of the diamond fold is turned back and pasted down as illustrated in Fig. 8. The bag blank is then passed to the 95 rollers 54, 55 where the bifurcated end 56 of the hook 57 supported on the frame folds the bag end back and on passing to the rollers 58, 59 the bag end having a certain amount of flexible spring or movement, the 100 end is folded over on the line or crease 48^a and the other portion or end 60 is gummed into the position as illustrated in Fig. 9.

The rollers 61, 62 are finishing rollers and are adapted to flatten the bag out, that is 105 to say, the diamond fold which is bent inwardly upon the crease 48^a, is opened out by being bent back on the crease 48^a, and the fold of the diamond is faced upwardly and the bag completed and delivered between 110 the rollers 61, 62.

This opening operation is effected by a knotted cord 63, arranged around pulleys 64, 65 and driven by sprocket and chain gear 66, from the spindle 67 of the upper finishing roller 61, which receives motion by spur gearing from the spindle 68 of the lower finishing roller 62.

This lower roller 62 is operated by a belt 69 from the spindle 70 of the lower roller 54 120 and the belt 69 carrying the bag forwardly and traveling at a lower speed than the knotted cord 63 allows the bag end to be engaged by the knot 71 of the cord which flattens the diamond fold out in its proper position preparatory to passing through the finishing rollers 61 and 62 which are preferably flattened at the point where they meet as the bag passes therethrough.

The driving gear has motion imparted 130

thereto from the belt pulleys 72 on the spindle 73 of the roller 58 and a chain 74 gears with a sprocket on the spindle 73 and engages sprockets on the lower rollers 22, 24, 5 42, 54 and 58. The upper roller 23 is connected by spur gears with the lower roller 24, and the upper roller 41 is connected by spur gears with the lower roller 42, while the upper rollers 55, 59, 61 have similar 10 gear connections with the lower rollers 54, 58 and 62 respectively, the drawing-in rollers 21 and 22 being the only rollers in frictional engagement with each other. Between the rollers 23, 24 and the rollers 41, 15 42 is a supporting plate 75 which supports the paper tube and a further supporting plate 76 is arranged between the rollers 41, 42 and the rollers 55, 54, the bag after it leaves the rollers 54, 55 being supported by 20 the belt 69 which is arranged centrally of the rollers.

All the upper rollers are adjustably mounted as illustrated more particularly in Figs. 18 and 19, the upper bearing block 25 77 of each upper roller being provided with a ball race 78 and ball bearings 79 to support the roller and being adjusted at the required pressure under the compression of the springs 80 arranged around the rods 90 extending 30 into the corresponding lower bearing block 91. The spindles of the lower rollers are mounted in cup and ball bearings 92 as illustrated more particularly in Fig. 19.

I desire it to be understood that the hooks 35 38, 52 and 57 may be mounted and arranged in any suitable way without departing from the spirit and scope of the invention provided they are adapted to perform the functions above described.

In the operation of the machine, the strip 8 is led from the roll 7 and passed around the roller 11 where it is gummed by the roller 12. It is then passed over the tem- 45 plet and folded around the same, is drawn between the guiding pulleys 17^a, through the friction drawing rollers 21, 22 and through the slitting and cutting rollers 23, 24 where the first portion of the diamond 50 fold and the thumb bits 34 are formed as illustrated in Fig. 7. The bag blank is then passed between the rollers 41, 42, where the edges 47 are gummed, the creases 48 and 48^a are formed and the end 53 turned over and 55 gummed down.

The bag blank is then passed between the rollers 54, 55 and by means of the bifurcated end 56 of the hook 57 is folded back on the crease 48^a and the end 60 is gummed 60 down to produce the position and folds indicated in Fig. 9.

After passing the rollers 58 and 59 the bag is flattened out in the proper position with the diamond fold upwardly by hav- 65 ing been engaged by the knot 71 of the cord

63 preparatory to passing through the finishing rollers 61 and 62.

An apparatus constructed and arranged as above described will be of great utility and simple and effective in operation as the 70 bag is not given any serious obstruction owing to the fact that it is passed in an approximately straight line through the machine from the templet to the finishing roll.

What I claim as my invention and desire 75 to secure by Letters Patent is—

1. A machine of the class described comprising in combination a supporting belt, a paper roll, guide rollers, a pasting roller, a templet, adjustable guiding rollers, drawing-in rollers, rollers adapted to part the bag blank and crease the same, parting knives mounted on the last-named rollers, a flexible rod having a projection thereon, a hook, a guide tongue, a supporting plate, 80 creasing and folding rollers, a paste roller associated therewith, a paste box, folding rollers in advance of the first-named folding rollers, a hook having a bifurcated end, folding rollers in advance of the second- 90 named folding rollers, a belt, a knotted endless cord, and finishing rollers, the various rollers being arranged in pairs one above the other with the several pairs disposed in line along the length of the machine. 95

2. In a paper bag machine, the combination of a pair of superposed rollers; a pair of knives mounted longitudinally on said rollers for coaction with each other, the knife on the upper roller having a groove 100 in its edge; and a flexible tongue extending between said rollers in the vertical plane of said groove and adapted to be pressed upwardly in the groove during the coaction of the knives, so as to form thumb bits on 105 the bag blank.

3. In a paper bag machine, the combination of a pair of superposed drawing-in rollers; a pair of superposed cutting rollers located directly in advance thereof, the upper rollers of both pairs having alining circumferential recesses; a pair of knives mounted longitudinally on the cutting rollers for coaction with each other, the knife on the upper roller having a groove in its edge 110 which is located within the recess in that roller; and a flexible tongue extending between said rollers and through the recesses in the vertical plane of the groove in said knife and adapted to be pressed upwardly in 115 the groove during the coaction of the knives, so as to form thumb bits on the bag blank.

4. In a paper bag machine, the combination of a pair of superposed rollers; a pair of knives mounted longitudinally on said 120 rollers for coaction with each other, the knife on the upper roller having a pair of spaced grooves in its edge; and a flexible rod having a forked end which extends between said rollers and the arms of which are dis- 125 130

posed in the vertical planes of said grooves, so that said arms will be pressed upwardly in the grooves during the coaction of the knives, in order to form thumb bits on the bag blank.

5. In a paper bag machine, the combination of a pair of coacting rollers, one having both a longitudinal ridge and a diagonal ridge, and the other having a longitudinal 10 groove and a diagonal groove to respectively receive the same; a pair of knives mounted longitudinally on said rollers for coaction with each other, the knife on the upper

roller having a pair of spaced grooves in its edge; and a spring tongue having a fork 15 which extends between said rollers and the arms of which are disposed in line with the grooves in said knife, so as to be pressed upwardly in said grooves during the coaction of the knives.

20 Signed at Melbourne, Victoria, Australia, this 31st day of May, 1920.

LESLIE WALTER WELSFORD.

In the presence of—

SIDNEY HENDLEY,

JEANNE BOUSHERE.
